Primary Examiner — Katie Jane Stofko(74) *Attorney, Agent, or Firm* — Merchant & Gould P.C.**CLAIM**

The ornamental design for a mineral pet chew as shown and described.

DESCRIPTION

FIG. 1 is a back, top and left side perspective view of a mineral pet chew;

FIG. 2 is a right side elevation view thereof;

FIG. 3 is a left side elevation view thereof;

FIG. 4 is a back elevation view thereof;

FIG. 5 is a front elevation view thereof;

FIG. 6 is a top plan view thereof; and,

FIG. 7 is a bottom plan view thereof.

The evenly-spaced broken lines in FIGS. 1-7 illustrate portions of the mineral pet chew that form no part of the claimed design. The dash-dot-dash broken lines in FIGS. 1 and 6 illustrate the boundary of the claimed design which forms no part thereof.

1 Claim, 7 Drawing Sheets(56)
